ATTORNEY

Arthur C. Evans Jr.
WITNESS:

UNITED STATES PATENT OFFICE

REUEL S. ROWE, OF RUTLAND, VERMONT

PAIL HOLDER

Application filed August 27, 1930. Serial No. 478,215.

This invention relates to a device for suspending paint pails from ladders. At present it is customary for painters to stand on ladders in the course of their work with their 5 paint pails attached to the rung of a ladder by means of a hook, attached to the pail handle. However this means of supporting a pail is found to be not only awkward and inconvenient because the center of the pail 10 is beneath the ladder rung on which it is suspended and only one half of the pail is inside the rung, and toward the painter, and therefore the present invention has as its 15 primary object to provide a more effective and more desirable means for supporting a paint pail from a ladder rung.

Another object of the invention is to provide a paint pail suspending attachment for a ladder which will be so constructed as to securely hold the pail and prevent any undue 20 swinging movement thereof while paint is being removed therefrom by the painter's brush, or due to wind.

This invention also consists in certain other 25 features of construction and in the combination and arrangement of the several parts, to be hereinafter fully described, illustrated in the accompanying drawings, and specifically pointed out in the appended claim, it being 30 understood of course that minor changes may be made so long as they fall within the scope of the claim.

In describing my invention in detail, reference will be had to the accompanying drawings, 35 wherein like characters denote like or corresponding parts throughout the several views, and in which:

Figure 1 is a view in elevation of the device 40 applied to a paint pail, the device being illustrated as suspended from one rung of a ladder, which ladder is shown in section.

Figure 2 is a view in front elevation of the device.

Figure 3 is a view in side elevation of the 45 device, partly in section.

The device embodying the invention is made from two pieces of strap iron and the device comprises a member 1 which is formed from such material so as to provide a straight shank portion 2, overturned at its upper end 50 to provide a hook 3 of approximately semi-circular form to engage over one rung of a ladder, from which rung the device and pail attached thereto are supported. The lower end of the shank 2 is deflected at an obtuse 55 angle as indicated by the numeral 4 and this portion is formed with a threaded opening 5 and a screw 6 having a winged head 7 which is adjustably threaded through the opening. The other member of the device is formed of 60 a material referred to above, and comprises a shank portion 8 which is disposed against that side of the shank portion 2 of the member 1 from which the hook 3 extends, and a member, last referred to, comprises, in addition to the shank portion 8, a clamp portion 9 which extends at an obtuse angle to the portion 8. Rivets 10 are secured through the shank portions 2 and 8 to the two members 65 and serve to hold the same assembled with 70 each other. As will be observed by reference to Figure 1, the device is to be mounted upon a ladder by engaging its hook 3 with a rung of the ladder and before the device is so engaged, the upper portion of the wall of the 75 pail to be suspended is inserted between the portions 4 and 9 of the two members 1 and 8, and the screw 6 is then tightened so as to cause the inner end thereof to bind this portion of the pail against the clamping member 9.

From the foregoing description of the invention it will be seen that a pail is supported in the most effective manner and with the 85 greatest degree of security, by the device embodying the invention, and in such position, with respect to the ladder, as to enable the painter to readily take up paint on his paint brush, from the pail.

What I claim is:

A pail holder comprising a shank member having one end curved to form a hook and the opposite end portion thereof disposed at an angle to the intermediate portion of the shank, a set screw threaded through said angularly disposed portion, a second shank member attached at one end to the intermediate portion of the first mentioned shank member and having an angularly disposed clamp portion spaced from and parallel with the angularly disposed end portion of the first mentioned shank member.

In testimony whereof I affix my signature.
